UNITED STATES PATENT OFFICE.

ALEXANDER EKLUND, OF ATTLEBORO, MASSACHUSETTS, ASSIGNOR TO
J. F. STURDY'S SONS, OF ATTLEBORO, MASSACHUSETTS, COPARTNERS.

BRACELET.

SPECIFICATION forming part of Letters Patent No. 783,626, dated February 28, 1905.

Application filed October 15, 1904. Serial No. 228,495.

To all whom it may concern:

Be it known that I, ALEXANDER EKLUND, a citizen of the United States, residing at Attleboro, in the county of Bristol and State of Massachusetts, have invented certain new and useful Improvements in Bracelets, of which the following is a specification, reference being had therein to the accompanying drawings.

My invention relates to concealed-joint bracelets, and has for its objects the ends commonly sought in this class of bracelets, but more particularly to provide a joint which, though concealed, discloses no gap when the bracelet is extended and is not liable to the fracture incident to pivot-pins and hinges, also to furnish a novel and efficient concealed means for joining the free ends of the bracelet-wings.

To the above ends my invention consists in the novel construction and combination of parts hereinafter described, and illustrated in the accompanying drawings, wherein—

Figure 1 is a side elevation of a complete bracelet embodying my invention, showing in broken lines the position of the joint; Figs. 2 and 3, vertical longitudinal sections of the free ends of the wings disengaged; Fig. 4, a similar section of the same engaged; Fig. 5, a transverse section of the bracelet on line xx of Fig. 1; Fig. 6, a rear elevation of the bracelet, showing the outer shell broken away from the back of the joint; Fig. 7, a side elevation of the tongue, and Fig. 8 a side elevation of inner face of one of the bearing-blocks.

Like reference-letters indicate like parts throughout the views.

My bracelet comprises two hollow sections or wings ab . A tongue c is soldered or otherwise fixed within the end of the wing a and is provided upon each side of its extremities with parallel ribs d , semicircularly disposed, as shown in Fig. 7. Bearing-blocks e and f are secured by solder or other appropriate means in the end of the section b . These blocks are provided upon the inner faces of their ex-

tremities with curved ribs g and slidably engage the ribs of the tongue c . In order to prevent disengagement and limit the excessive travel of the tongue c , a stud h is placed intermediate the ribs d on each side of the tongue c and registers in a slot i in one of the ribs g of the bearing-blocks e and f . The bearing-blocks e and f may be made of one piece, if preferred.

Referring now to the fastening means of my bracelet, there is pivotally mounted at its inner extremity upon a pin j in the free end of the wing b a latch k , above which is an orifice l in the bracelet-section. In the corresponding end of the wing a is an opening m , adapted to receive the latch, and in the rear of which is a block n , supporting a flat spring o with a slightly-curved extremity. This spring is adapted to guide and retain latch k upward into engagement with the shoulder p , formed by the orifice m in the extremity of the wing a .

To disengage the catch of my bracelet, the wearer inserts a pin or other sharp implement into the opening l and forces the latch k downwardly against the tension of spring o , which yielding frees the latch from the shoulder p and forces the wings or sections asunder, as shown in Figs. 2 and 3.

Having described my invention, what I claim is—

1. A bracelet comprising a plurality of sections hinged together, the hinge consisting of an interengaging tongue and bearing-blocks within the ends of the adjoining sections, and means intermediate the tongue and bearing-blocks for limiting the travel of the tongue whereby a concealed joint entirely within the sections is provided.

2. A bracelet comprising a plurality of hollow sections hinged together, said hinge consisting of a tongue fixed within the end of one section and provided upon each side of its extremities with parallel ribs semicircularly disposed, and bearing-blocks secured within the adjacent end of the adjoining section and pro-

vided upon the inner faces of their extremities with curved ribs slidably engaged with the ribs of the tongue and confining the latter, one of said ribs of the bearing-blocks being provided with a slot and a stud intermediate the ribs of the tongue and registering with said slot.

In testimony whereof I have affixed my signature in presence of two witnesses.

ALEXANDER EKLUND.
